US00D931951S

(12) **United States Design Patent** (10) Patent No.: **US D931,951 S**
(45) Date of Patent: **** Sep. 28, 2021**

(54) **RADIO CONTROL DEVICE FOR HOBBY MODELS**

(71) Applicant: **Futaba Corporation**, Mabora (JP)

(72) Inventors: **Takahiro Isono**, Mabora (JP); **Makoto Migita**, Tokyo (JP)

(73) Assignee: **Futaba Corporation**, Mabora (JP)

(**) Term: **15 Years**

(21) Appl. No.: **29/698,809**

(22) Filed: **Jul. 19, 2019**

(30) **Foreign Application Priority Data**

Jan. 24, 2019 (JP) 2019-001296

(51) **LOC (13) Cl.** **21-01**

(52) **U.S. Cl.**

USPC **D21/566**

(58) **Field of Classification Search**

USPC D21/566, 568, 567, 569, 570, 571, 436, D21/441, 453, 454; D12/16.1; D14/496

CPC G08C 17/02; A63H 30/04; A63H 29/22;

A63H 27/02

(57) **CLAIM**

We claim the ornamental design for a radio control device for hobby models, as shown and described.

DESCRIPTION

FIG. 1 is a front view of a radio control device for hobby models;

FIG. 2 is a rear view of FIG. 1;

FIG. 3 is a top view of FIG. 1;

FIG. 4 is a bottom view of FIG. 1;

FIG. 5 is a right side view of FIG. 1;

FIG. 6 is a left side view of FIG. 1;

FIG. 7 is a front, top, and right side perspective view of FIG. 1;

FIG. 8 is a rear, top, and left side perspective view of FIG. 1; and,

FIG. 9 is a perspective view of FIG. 1 similar to the perspective of FIG. 7 showing the antenna standing.

1 Claim, 9 Drawing Sheets
